(57) **CLAIM**

We claim the ornamental design for a wireless transceiver for controlling professional visual effects devices.

DESCRIPTION

FIG. 1 is a side perspective view of the wireless transceiver for controlling professional visual effects devices.

FIG. 2 is a top view of the wireless transceiver for controlling professional visual effects devices.

FIG. 3 is a bottom view of the wireless transceiver for controlling professional visual effects devices.

FIG. 4 is a right side view of the wireless transceiver for controlling professional visual effects devices.

FIG. 5 is a left side view of the wireless transceiver for controlling professional visual effects devices.

FIG. 6 is a front view of the wireless transceiver for controlling professional visual effects devices; and,

FIG. 7 is a back view of the wireless transceiver for controlling professional visual effects devices.
